GAS-TURBINE.

1,031,718.

Specification of Letters Patent.

Patented July 9, 1912.

Application filed September 22, 1910. Serial No. 583,204.

To all whom it may concern:

Be it known that I, ALEXANDER T. KASLEY, a citizen of the United States, and a resident of Swissvale, in the county of Allegheny and State of Pennsylvania, have made a new and useful Invention in Gas-Turbines, of which the following is a specification.

This invention relates to turbines and particularly to gas turbines.

An object of my invention is to produce means for employing the expansive force resulting from the combustion of a combustible or explosive mixture and also for controlling the heat energy evolved by the combustion.

A further object is to produce a gas turbine, in which means are employed for reducing the temperatures of the gases delivered to the turbine blades or buckets.

A further object is to produce a new and improved valve mechanism for controlling the delivery of gases to the gas turbine.

These and other objects I attain in an apparatus embodying the features herein described and illustrated in the drawings accompanying this application and forming a part thereof.

In the drawing: Figure 1 is a partial section and partial elevation of a more or less diagrammatic arrangement of apparatus embodying my invention. The section of the gas turbine and delivery or distributing valve is taken on the line 1—1 of Fig. 5; Fig. 2 is a plan view of a portion of the apparatus shown in Fig. 1; Fig. 3 is a section along the line 3—3 of Fig. 1; Fig. 4 is a sectional view along the line 4—4 of Fig. 1 looking in the direction of the arrows; Fig. 5 is a sectional view looking in the direction of the arrows on the broken line 5—5 of Fig. 1, and discloses a distributing valve for controlling the delivery of the products of combustion to the gas turbine; Figs. 6, 7 and 8 are elevations of the valve shown in Fig. 5 and illustrate the positions of the valve during successive steps in the cycle of operation of the apparatus; Fig. 9 is a sectional view along the line 9—9 of Fig. 8; and Fig. 10 is a diagrammatic sectional view and illustrates a developed section of a valve corresponding to the valve illustrated in Fig. 5.

Referring to the drawings: The apparatus illustrated as an embodiment of my invention includes four combustion chambers 11, 12, 13 and 14, in which combustible or explosive mixtures, preferably of gas and air, are successively introduced, compressed and fired. The apparatus also includes a gas turbine 15 operated by the expansive force of the combustion or the explosions in the combustion chambers, and a steam turbine 16 operated by steam generated by the sensible heat of the combustion in the combustion chambers and by the sensible heat of the products of combustion passing to the gas turbine. In addition to this, I have disclosed a valve 17 for controlling the delivery of the products of combustion from the combustion chambers to the gas turbine, and a valve mechanism for controlling the delivery of combustible mixture or charge to the combustion chambers.

The combustion chambers 11, 12, 13 and 14 are located in a receptacle 18, which is adapted to be filled with water and communicates with steam piping 19, through a port 20, for the purpose of delivering steam to the steam turbine 16. The walls of the combustion chambers are shown formed integrally with the head portion 21 of the receptacle 18 and are provided with ports 22 located in the head portion. This construction, however, is merely illustrative, as it may be desirable to form the chambers separately.

The mixture of gas and air is delivered to the combustion chambers through the ports 22 and each port is controlled by a valve 23. The interiors of the combustion chambers 11, 12, 13 and 14 respectively communicate with discharge ports 24, 25, 26 and 27 through tubes 28, which extend through the lower portion of the receptacle and are secured in place in any well known manner, in the lower heads of the chambers. The receptacle 18, the combustion chambers and the tubes 28 form in effect a boiler, which converts the sensible heat of the combustion in the combustion chambers, and the sensible heat of the gases passing to the gas turbine into fluid pressure and provides a source of motive fluid for the turbine 16.

The gas turbine 15 illustrated consists of a row of blades or buckets 29 mounted on a

wheel 30 which is mounted on a shaft 31. The products of combustion from the separate combustion chambers are delivered to the blades 29 by nozzles provided in the valve 17, which, in the apparatus illustrated, forms in effect a casing for the turbine wheel 30.

A compressor for the air and gas delivered to the combustion chamber is shown 10 operated by the shaft 31 of the gas turbine, and is adapted to slightly compress and deliver the air and gas to the combustion chambers. The compressor comprises an impeller 33 inclosed within a casing 34 and 15 mounted on the shaft 31. The working passages of the impeller are divided by a diaphragm 35 so that the air is compressed on one side of the impeller and the gas on the other. Air enters the casing 34 through 20 a port 36 which surrounds the shaft 31 and gas enters the casing through a flanged port 37, which may communicate with a suitable source of gas supply through piping, not shown. Air is discharged from the compressor 25 through the piping 38, and gas through piping 39.

The steam turbine 16 is illustrated in 30 fragmental elevation. Any type of turbine may be employed and the turbine may be, and preferably is, employed with a condenser. The rotor element of the turbine illustrated is directly connected to the shaft 31 of the gas turbine and the compressor, and is inclosed within a stationary casing, 35 provided with an admission port communicating with the piping 19.

Any type of valve mechanism may be employed for delivering the gas and air to the 40 separate combustion chambers. In the drawings, I have illustrated a mixing valve for each combustion chamber, which consists of a cylindrical casing 40, provided with gas and air discharge ports 41 and 42, and inclosing a rotatable slide 43, which is 45 rotatably mounted on, and surrounds the stem of the valve 23. The slide 43 of each mixing valve is adapted to reciprocate with the corresponding valve 23 and is provided with ports which register with, and uncover, 50 the ports 41 and 42 of the casing 40 when the valve 23 is in the open position. An arm 44 is provided on the top cover of each casing 40 and is adapted to be moved to different positions by a speed governor, for 55 the purpose of rotating the slide 43 and varying the amount of opening of the ports 41 and 42 in accordance with the variation of the speed of the gas turbine 15. The cylindrical casings 40 of the four mixing 60 valves are shown formed in a single casing, which is provided with separate gas and air delivery passages, which respectively communicate with the piping 39 and 38 and with the respective ports 41 and 42 of the 65 casings. This construction, however, is

merely illustrative, as it may be desirable to form each casing separately.

The stem of each valve 23 projects upwardly through the cover of the cylindrical casing 40 and is engaged by a cam 45 or by 70 a cam actuated mechanism, which is adapted to open the valve and deliver mixture to the combustion chamber. A coiled spring 46 is shown located within each casing 40 and is adapted to close the valve 23 at the 75 proper time during the cycle of the apparatus and shut off the flow of gas and air to the combustion chamber and confine the charge in the chamber. The cams 45 are diagrammatically shown, and it will be apparent that any suitable mechanism for actuating the valves 23 may be employed. The cams 45 are shown as mounted on a cam shaft 47, which is operated through 80 suitable gearing by the shaft 31 of the gas 85 turbine 15.

The apparatus is so arranged that charges 90 of gas and air are successively delivered to the combustion chambers, and the charges so delivered are then initially compressed, finally compressed, fired, expanded in three 95 distinct steps and then blown out of the combustion chambers by the incoming charge of fresh mixture. Each step takes place successively in the series of chambers so that the 100 chambers are fired, one at a time and in succession. In carrying out these steps, I employ the distributing valve 17, which is rotatably mounted on ball bearings, in a casing 48, and is driven by means of a spur wheel 49, which meshes with teeth, formed on the 105 outer periphery of the valve, and is driven through suitable gearing by the shaft 31. The valve is so arranged that the discharge ports of each combustion chamber is blocked off or closed during the firing period of the chamber. In addition to this, the valve is so formed that the expansive force, resulting from the explosion in the chamber, is employed in finally compressing the charge 110 in another chamber and then initially compressing the charge in still a second chamber of the series, after it has imparted energy to the gas turbine.

The valve is provided with a blank 51, 115 which is adapted to successively close the discharge ports of the combustion chambers during the rotation of the valve. A nozzle 52 (Fig. 10) is located adjacent to the blank 51 and is adapted to successively communicate with the discharge ports of the combustion chambers and to deliver the initial expansion, resulting after the combustion in the combustion chambers, to the blades 29 of the turbine. A passage 53 is formed in 120 the valve and is adapted to receive the gases delivered by the nozzle 52, after they have traversed the blades 29, and to re-direct them and deliver them, through one of the discharge ports, into one of the chambers of 125 130

the series for the purpose of finally compressing the charge in that series. A nozzle 54 is formed in the valve adjacent to the nozzle 52 and is adapted to successively register with the discharge ports and to discharge the flow of gases resulting from the continued or secondary expansion in the combustion chambers, to the blades 29. A passage 55 provided in the valve is so located that it receives the fluid discharged from the nozzle 54, after it has traversed the blades 29, and re-directing it, delivers it to one of the combustion chambers of the series for the purpose of initially compressing the charge in that chamber. A nozzle 56 is provided in the valve adjacent to the nozzle 54 and is adapted to successively register with the delivery ports of the combustion chambers and to discharge the fluid through the blades 29 and into an exhaust passage 57 formed in the valve. The exhaust passage 57 may communicate with the atmosphere, if desired. An exhaust passage 58 is provided in the valve adjacent to the nozzle 56 and is adapted to successively register with the discharge ports and to directly connect them with the exhaust, without causing the fluid, issuing through them, to traverse the blades 29 of the wheel. The valve rotates in the direction of the arrows in Figs. 5, 6, 7, 8 and 10 and the turbine wheel 30 rotates in the opposite direction.

In Figs. 5, 6, 7 and 8 of the drawings, I have illustrated successive positions of the valve 15 during the operation of the apparatus. In these drawings, I have indicated the positions of the discharge ports 24, 25, 26 and 27, which communicate with the respective chambers 11, 12, 13 and 14 by means of broken line circles cross-hatched with broken lines.

In Fig. 5 the valve 17 is in the position it will occupy during the firing period of the chamber 12. The blank 51 is shown covering the port 25; the passage 55 is shown in the position for delivering the products of combustion from the combustion chamber 11 into the combustion chamber 13, for the purpose of primarily compressing the charge in the chamber 13; the passage 58 is shown in direct communication with the port 27 and consequently with the chamber 14, and the passage 53 is blocked off and is unopened. In this position of the valve 17, the chamber 14 is receiving a fresh charge and the inert gases, resulting from the previous combustion in the chamber, are being blown out into the exhaust by the incoming fresh charge. The diagram in Fig. 10 corresponds to the location of the valve shown in Fig. 5.

In Fig. 6, the valve 17 is shown in the next position. The passage 53 is in the position for delivering the flow of gas, resulting from the initial expansion in the

chamber 12, into the chamber 11, for the purpose of finally compressing the charge in that chamber; the passage 55 is blocked off and is inoperative; the passage 58 is still in communication with the port 27 and the passage 57 is in the position to discharge the gases issuing from the chamber 13 directly to the exhaust after they have traversed the blades 29 of the gas turbine.

In Fig. 7, the valve is shown in the position it will occupy during the firing period of the chamber 11, the period in which the force of the expansion in the chamber 12 is initially compressing the charge in the chamber 14, and the chamber 13 is being scavenged by the admission of a fresh charge. The passages 53 and 57 are blocked off and inoperative.

In Fig. 8, the valve 17 is shown turned to the position in which the force of the initial expansion in the chamber 11 is finally compressing the charge in the chamber 14, the final expansion in the chamber 12 is being discharged through the blades 29 to the exhaust and the chamber 13 is being finally scavenged and charged. The passage 55 is blocked off and inoperative.

During the operation of the apparatus, I find it preferable to only partially scavenge the combustion chambers. I prefer to leave inert gas, resulting from the previous combustion, in the tubes 28 communicating with the chamber. At the end of the scavenging and charging period, the valve 23, controlling the delivery of mixture to the chamber, is closed and the charge is initially compressed. This initial compression tends to force inert, but hot gases, from the compressing chamber into the tubes 28 communicating with the chamber, in which the charge is to be compressed. During the final compression, hotter gases, existing at a higher pressure, are forced into the tubes communicating with the chamber under-going compression, and the line of division between the charge and the inert gas in the chamber is raised, as the pressure in the chamber increases. The chambers are preferably made long in proportion to their diameters, so that marked stratification will exist. Each chamber may be fired by any suitable means. In the drawings, I have illustrated an electric spark plug 61 of ordinary construction, to which the delivery of current may be controlled by a timing device (not shown), which may be actuated by the operating mechanism of the valves 23.

As has been stated, the discharge ports, communicating with the combustion chambers, are closed during the firing period; consequently the explosion in each chamber will result in an expansion of the gases and a piling up of pressure. When the discharge port, communicating with the chamber fired, is opened, a flow of gas to the gas

turbine will be induced by the high pressure. It will be apparent, however, that the gas first entering the blades 29 of the gas turbine is the inert and the relatively cool gas delivered to the tubes 28 during the periods of compression. With this arrangement, the hot gases, resulting from an explosion, are maintained in the chamber long enough to cool them considerably by expansion and to impart a portion of their sensible heat to the water in the receptacle 18. The gases are further cooled while passing through the tubes 28 and are reduced in temperature to such an extent before being delivered to the blades 29 that they will not burn out or detrimentally affect the blades.

In the drawings, I have shown a governor 63, which is driven by the steam and gas turbines and is arranged to vary the position of the arms 44 of the mixing valves delivering mixture to the chambers 11, 12, 13 and 14. The governor is shown diagrammatic and is connected by means of a diaphragmatic arrangement of levers and bell-crank arms with the arms 44. The mixing valves illustrated are adapted to control the quantity of mixture delivered to each chamber. It will be apparent, to those skilled in the art, that mixing valves may be employed, similar to those illustrated, which will vary the quantity and the quality of the mixture delivered. I have also shown a butterfly valve 62 in the inlet port 37 of the compressor. This valve is employed for the purpose of varying the quality of the mixture delivered by the compressor to the mixing valves and may be operated by hand or by the governor.

It will be apparent that the steam turbine 40 16 and the compressor need not necessarily be directly connected to the shaft of the gas turbine and that the apparatus illustrated is merely illustrative and may be materially modified and varied without departing from the spirit and scope of my invention.

Having thus described my invention, what I claim is:

1. In combination with a gas turbine, combustion chambers, means for delivering a combustible charge to said chambers and means for causing the expansive force in one chamber to directly compress the charge in another chamber.

2. In combination with a gas turbine, 55 combustion chambers, means for delivering a combustible charge to said chambers and means for causing the expansive force in one chamber to compress the charge in another chamber after it has imparted energy 60 to said turbine.

3. In combination with a gas turbine, combustion chambers, means for delivering a combustible charge to said chambers and means for controlling the delivery of the 65 products of combustion from said chamber

to said turbine and for causing the expansive force resulting from the combustion in one chamber to directly compress the charge in another chamber.

4. In combination with a gas turbine, 70 combustion chambers, means for delivering a combustible charge to said chambers, means for causing the expansive force resulting from the combustion in one chamber to directly compress the charge in another 75 chamber and means for cooling the products of combustion prior to delivery to said turbine.

5. In combination with a gas turbine, combustion chambers, means for delivering 80 a combustible charge to said chambers, means for controlling the delivery of the products of combustion from said chamber to said turbine and for causing the expansive force resulting from the combustion in 85 one chamber to directly compress the charge in another chamber and means for cooling the products of combustion prior to delivery to said turbine.

6. In combination with a gas turbine, 90 combustion chambers, means for delivering a combustible charge to said chambers and a distributing valve for controlling the delivery of the products of combustion from said chambers to said turbine and for conducting the gases from one chamber to another chamber for the purpose of compressing the charge.

7. In combination with a gas turbine, combustion chambers, means for periodically 100 delivering combustible charges to said chambers, a distributing valve for controlling the delivery of the products of combustion from said chambers to said turbine and for conducting the gases from one 105 chamber to another of said chambers for the purpose of compressing the charge and means for cooling the products of combustion prior to delivery to said turbine and for conserving the heat energy derived 110 therefrom.

8. In combination with a gas turbine, a series of combustion chambers, means for successively delivering a combustible mixture to the chambers of the series, means for 115 successively firing the charges in said chambers and means for employing the expansive force in one chamber of the series for directly compressing the charge in another chamber.

9. In combination with a gas turbine, a series of combustion chambers, means for successively delivering combustible mixture to said chambers, means for successively firing the mixtures in the chambers and means 125 for employing the expansive force of two of the chambers of the series in directly compressing the charge in one of the chambers of the series.

10. In combination with a gas turbine, a 130

- series of combustion chambers, means for successively delivering combustible mixture to said chambers and means for delivering the products of combustion from the chambers to the turbine and for employing the expansive force, resulting from the combustion in one chamber in directly compressing the combustible mixture in another chamber, after it has imparted energy to the turbine. 5
11. In combination with a gas turbine, a series of combustion chambers, means for successively delivering combustible mixtures to said chambers, means for successively firing the charges in said chambers and means for delivering the products of combustion to the turbine and for employing the expansive force to two chambers of the series in directly compressing the explosive mixture in one chamber of the series after it has imparted energy to the turbine. 10
12. In combination with a gas turbine, a series of combustion chambers, means for delivering combustible mixtures to said chambers and means for causing the expansive force resulting from the combustion in one chamber to successively and directly compress the charge in two of the other chambers of the series. 15
13. In combination with a gas turbine, a series of combustion chambers, means for delivering combustible mixtures to said chambers and means for causing the expansive force resulting from the combustion in one chamber to successively and directly compress the charge in two of the other chambers of the series after having imparted energy to the turbine. 20
14. In combination with a gas turbine, a series of combustion chambers, means for delivering combustible mixture to said chambers, means for causing the expansive force resulting from the combustion in one chamber to successively and directly compress the charge in two of the other chambers of the series and means for cooling the products of combustion and for conserving the heat energy derived therefrom prior to delivery to the turbine. 25
15. In combination with a gas turbine, a series of combustion chambers, means for successively delivering combustible charges to said chambers, means for successively firing the charges in said chambers and means for causing the expansive force resulting from the combustion in said chambers to successively and directly compress the charges in the successive chambers of the series. 30
16. In combination with a gas turbine, a series of combustion chambers, means for successively delivering combustible charges to said chambers, means for successively firing the charges in said chambers and means for delivering the products of combustion from said chambers to said turbine and for causing the expansive force resulting from the combustion in the successive chambers to successively compress the charges in the chambers after it has imparted energy to said turbine. 35
17. In combination with a gas turbine, a series of combustion chambers, means for successively delivering combustible charges to said chambers, means for successively firing said chambers, means for delivering the products of combustion from said chambers to said turbine and for causing the expansive force resulting from the combustion in the successive chambers to successively compress the charges in the chambers after it has imparted energy to said turbine. 40
18. In combination with a gas turbine, a series of combustion chambers, means for successively delivering combustible charges to said chambers, means for causing the expansive force resulting from the combustion in each chamber to successively compress the charges in two successive chambers of the series after having imparted energy to the turbine and means for cooling the products of combustion and for conserving the heat energy derived therefrom. 45
19. In combination with a gas turbine, a plurality of combustion chambers, means for delivering a combustible charge to each chamber and means for introducing the products of combustion from one chamber into a second chamber for the purpose of compressing the charge contained in that chamber. 50
20. In combination with a gas turbine, a plurality of combustion chambers, means for delivering a combustible charge to each chamber and means for delivering the products of combustion from said chambers to said turbine and means for introducing the products discharged from the turbine into a second chamber for the purpose of compressing the charge contained therein. 55
21. In combination with a gas turbine, a plurality of combustion chambers, means for delivering a combustible charge to each chamber and means for introducing the products of combustion from one chamber into two other chambers for the purpose of compressing the charge in the other chambers. 60
22. In combination with a gas turbine, a series of combustion chambers, means for delivering a combustible charge to each chamber and means for delivering the products of combustion from said chambers to said turbine and for introducing the products of combustion discharged from the turbine into two of the chambers of said series for the purpose of compressing the charge contained therein. 65
23. In combination with a gas turbine, a series of combustion chambers, means for delivering a combustible charge to each chamber, means for delivering the products of combustion from said chambers to said turbine and for causing the expansive force resulting from the combustion in the successive chambers to successively compress the charges in the chambers after it has imparted energy to said turbine. 70

turbine and for introducing the products of combustion discharged from the turbine into two of the chambers of said series for the purpose of compressing the charge contained therein and means for cooling the products of combustion prior to their admission to the turbine and for conserving the heat energy derived therefrom.

24. In combination with a gas turbine, a plurality of water cooled combustion chambers, means for delivering combustible charges to said chambers, cooling tubes communicating with said chambers for delivering the products of combustion to said turbine, and a valve for controlling the delivery from said chambers to said turbine and for re-directing the products of combustion from said turbine into said chambers for the purpose of compressing the fresh charges contained therein.

25. In combination with a gas turbine, a series of water cooled combustion chambers, means for delivering combustible charges to said chambers, cooling tubes communicating with said chambers for delivering the products of combustion from said chambers to said turbine and a valve for controlling the delivery from said tubes to said turbine and for re-directing the products of combustion discharged from said turbine into said tubes for the purpose of compressing the fresh charge contained in the chambers communicating therewith.

26. In combination, a plurality of com-

bustion chambers and a gas turbine comprising a rotatable wheel provided with buckets and a distributing valve inclosing said wheel and provided with gas delivery passages for successively communicating with said chambers.

27. In combination, a plurality of combustion chambers, a gas turbine comprising a rotatable wheel provided with buckets and a rotatable distributing valve inclosing said wheel and provided with gas delivery nozzles for successively communicating with said chambers and gas discharge passages for receiving the gases discharged from said turbine and for re-directing them into said chambers.

28. A gas turbine, comprising a wheel provided with buckets and a rotatable casing provided with fluid delivery nozzles for delivering gas to said buckets.

29. A gas turbine comprising a wheel provided with buckets, a rotatable casing provided with fluid delivery nozzles for delivering gas to said buckets and discharge passages for receiving and re-directing the gases discharged from said turbine.

In testimony whereof, I have hereunto subscribed my name this 17th day of Sept., 1910.

ALEXANDER T. KASLEY.
